T. J. TUNE,
TELEPHONE SYSTEM WITH INSTANTANEOUS DISCONNECT AND RECALL,
APPLICATION FILED OCT. 10, 1914.

1,276,997.

Patented Aug. 27, 1918.

UNITED STATES PATENT OFFICE.

THOMAS J. TUNE, OF CLEVELAND, OHIO, ASSIGNOR TO KELLOGG SWITCHBOARD & SUPPLY COMPANY, OF CHICAGO, ILLINOIS, A CORPORATION OF ILLINOIS.

TELEPHONE SYSTEM WITH INSTANTANEOUS DISCONNECT AND RECALL.

Specification of Letters Patent.

Patented Aug. 27, 1918.

1,276,997.

Application filed October 10, 1914. Serial No. 865,983.

To all whom it may concern:

Be it known that I, THOMAS J. TUNE, a citizen of the United States of America, residing in Cleveland, county of Cuyahoga, 5 State of Ohio, have invented certain new and useful Improvements in Telephone Systems with Instantaneous Disconnects and Recalls, of which the following is a specification.

10 My invention pertains to telephone systems having operator's cord circuits employing instantaneous disconnect circuits, and has to do more particularly with the provision of control circuits whereby she may 15 again operatively associate the cord circuit with a line over which a recall has been initiated and also associate her telephone with the cord.

In certain systems of the above character 20 cord circuits are so arranged that a subscriber by replacing his receiver upon its switch-hook, while the cord circuit is connected with his line, effects instantaneous disconnection of the cord conductors from his line so that a subsequent removal of the receiver will again light his line lamp to indicate a recall even though the cord circuit is still connected with his line. In systems of this character wherein automatic 25 listening is provided, that is the automatic connection and disconnection of the operator's telephone by the insertion of the answering and calling plugs, should a subscriber attempt a recall the operator must 30 remove one or both plugs from their connected jacks before she can converse with the subscriber who has initiated such recall. In order to obviate such disconnection of the plugs responsive to a recall, I provide 35 an operator's key controlled circuit whereby when a cord circuit is operatively disassociated from a line and a recall initiated, the actuation of such key will operatively connect the cord circuit to the recalling line 40 and conductively unite its ends, at the same time connecting her telephone set with the talking conductors of the cord so that she can converse with the recalling subscriber.

In the accompanying drawing, I have 50 illustrated the preferred embodiment of my invention, and I have shown two substations A and C terminating in line circuits L and L¹ adapted for interconnection by an oper-

ator's cord circuit B. The line circuits are of a well-known two-wire type including 55 line and cut-off relays. The cord circuit is also of a well-known type and comprises an answering sleeve relay AS, an answering tip relay AT, a calling sleeve relay CS, and a calling tip relay CT. I also provide a 60 link disconnect relay LD which is energized to operatively disconnect the link circuit from a connected calling line when the subscriber at the substation replaces his receiver. A recall key RE is also provided 65 which the operator actuates upon receiving a recall signal whereby the link disconnect relay LD is restored and the operator's telephone O connected to the talking conductors of the cord.

70 I also provide automatic connecting and disconnecting means for the operator's telephone, including contacts on the answering and calling sleeve relays.

A register device for recording calls is 75 also provided and includes a meter relay MR and meter magnet MM which are operated through contacts of the answering tip relay when a call is answered.

Automatic ringing apparatus is also provided comprising a well-known type of harmonic ringing controlled by a ringing key RK, a ringing control relay RC and an interrupter relay IR. The ringing key includes four ringing contacts and a common 80 contact 1 which is adapted to be closed only while the ringing plungers are in a fully actuated position. When the ringing plunger returns to its intermediate or indicating position, the ringing contacts remain closed, 85 but the common contact 1 is again opened. The operation of the ringing key locks the ringing control relay RC in its energized position whereby the interrupter relay IR is operated to intermittently apply ringing 90 current to the called line. When a subscriber responds, the calling tip relay CT is energized causing the restoration of the ringing control relay which renders the interrupter relay IR inert. I also provide 95 ringing indicating means in the form of a winding 2 preferably of few turns upon the answering tip relay which winding is included in the ringing circuit so that its inductive effect upon the main winding of the 100 answering tip relay will apprise the calling 105

subscriber of the fact that the called line is being rung.

Operation.

- 5 Having described in a general way the apparatus employed in my invention as illustrated, its operation in establishing a connection between substations A and C will now be described more in detail. To initiate 10 a call the subscriber at substation A removes his receiver establishing an energizing circuit for the line relay LR and lighting the line lamp 3. The operator in response to this signal inserts the answering plug AP 15 into the answering jack of the calling line whereby relays CO and AS are connected in series causing the energization of both. The operation of CO connects the answering jack to the calling line and restores the line 20 relay and thereafter the answering tip relay AT is energized by current flowing from battery through the winding of AS over the calling line and returning through the winding of AT to ground. The closing 25 of alternate contact 4 of relay AT operates the call meter and the closing of alternate contacts 5, 6 of relay AS connects the operator's telephone O through normal contacts 7, 8 to the talking conductors of the cord. The operator now ascertains the number of the wanted substation and upon testing the wanted line in the usual manner, and finding it idle, inserts the calling plug CP into a jack thereof. 30 This act connects the calling sleeve relay CS and cut-off relay CO¹ in series causing the energization of both. The closing of alternate contact 9 of relay CS establishes a circuit for the calling supervisory lamp 35 signal CL through normal contacts 10 and 11. The interruption of normal contacts 7, 8 disconnects the operator's telephone, thereby giving automatic disconnection. 40 The operator now depresses the proper 45 ringing plunger, thereby momentarily closing the common contacts 1 of the ringing key whereby a circuit for the ringing control relay RC is established traced from battery through the winding thereof, contacts 1 to ground at alternate contact 9. Relay RC therefore energizes interrupting the talking conductors at normal contacts 12 and 13, and the closing of alternate contact 14 establishes an operating circuit for 50 the interrupter relay IR. The interruption of normal contact 11 of relay RC effaces the calling supervisory or clearing out signal CL and the closing of alternate contact 11 lights the ringing lamp RL. The initial 55 energizing circuit for RC being only of momentary duration through contact 1, a locking circuit for this relay is provided traced back over conductor 15, normal contact 16, alternate contact 11, normal contact 60 65 10 and alternate contact 9 to ground. The

ringing current from the connected generator traverses a path including alternate contact 18, tip conductor of the cord returning over the connected line, part flowing through relay CS and part through alternate contact 13 and the signal back winding 2. Due to the inductive effect of the ringing current through winding 2 upon the energizing winding of relay AT, the calling subscriber receives an indication that ringing current 75 is being applied to a called line.

Upon response of the called subscriber and the first following deenergization of relay IR, a circuit for the calling tip relay CT is established through normal contact 18 80 so that relay CT is energized by current flowing through CS and over the called line. Relay CT therefore interrupts its normal contact 10, and as this contact is included in the circuits of relay RC and ringing lamp 85 RL they are rendered inert. Upon restoration of relay RC the talking conductors of the cord are rendered continuous and the interruption of alternate contact 14 prevents further operations of the interrupter relay 90 IR. The interruption of alternate contact 13 of RC disconnects the signal back winding 2.

Upon completing conversation and assuming the subscribers desire disconnection, 95 they replace their receivers upon their respective switch-hooks, interrupting the circuits for tip relays AT and CT. The ensuing deenergization of CT establishes a circuit for the supervisory lamp CL and the 100 deenergization of relay AT establishes a circuit for the answering supervisory lamp AL. The circuit for AL may be traced from battery through the lamp, normal contact 20, alternate contact 21, to ground at 105 alternate contact 9. This ground connection to normal contact 20 also establishes a circuit for the link disconnect relay LD whereupon it is energized interrupting normal contacts 22, 23, to operatively disassociate the link 110 talking conductors from the calling line and the sleeve relay AS is maintained energized through alternate contacts 25, 21 and 9 to ground. As above stated, it has been assumed that the subscribers replaced their 115 receivers for disconnection, in which case the operator observing the lighting of the supervisory lamps AL and CL withdraws the plugs from their respective jacks. The relay CS therefore is restored interrupting 120 the alternate contact 9 which has been maintaining relays LD and AS energized and lamps AL and CL lighted, so that these four elements are restored to normal.

Assuming now that a connection had been 125 established between substations A and C and upon finishing conversation, the subscriber at A initiates a recall by again removing his receiver prior to the withdrawal of the plugs from their jacks.

It will be remembered that when the subscribers at stations A and C replace their receivers, disconnect relay LD was operated to disconnect the link conductors from the line of substation A. This of course results in the restoration of the cut-off relay CO so that the subscriber at A upon again removing his receiver before the plug AP has been withdrawn, effects the lighting of his line lamp 3. Although the operator has received a disconnect signal by the operation of lamps AL and CL, she also observes that the lamp 3 associated with the answering jack in which plug AP is inserted, has been lighted, and knows that her attention is desired. Therefore, it is not necessary that she withdraw either of the plugs from their connected jacks in order to be able to again connect her telephone to the cord circuit, but she need only actuate the recall key RE. This interrupts the circuit for the link disconnects relay LD whereupon it restores and operatively connects the link talking conductors to the recalling line. As before, this act causes relays AS, CO and AT to be energized, and the closing of alternate contacts 27, 28 of the recall key connects the operator's telephone to the cord talking conductors so that her telephone set is operatively associated with both ends of the cord and she may converse with the calling subscriber to ascertain his wants.

From the above, it will be seen that when a recall is initiated and both plugs remain in connection with line jacks, although the original listening circuit is not effective on account of the interruption of contacts 7, 8, of relay CS, the operator by the actuation of her recall key, unites her telephone with both ends of the cord circuit without having to remove either plug from the jack.

Having described my invention what I claim as new and desire to secure by Letters Patent is:

1. A telephone system comprising telephone lines, an operator's cord circuit for connecting calling and called lines, an operator's telephone, automatic means for connecting and disconnecting said operator's telephone and said cord circuit, cord disconnect means responsive to the replacing of the receiver of a connected line upon its switch-hook, and operator key controlled circuits for reconnecting the cord to the last said line and connecting the operator's telephone to the cord without the removal of either plug from its connected jack.

2. A telephone system comprising telephone lines, an operator's cord circuit for connecting calling and called lines, an operator's telephone, automatic means for connecting and disconnecting said operator's telephone and said cord circuit, cord disconnect means responsive to the replacing of the receiver of a connected line upon its switch-

hook, an operator's key, and control circuits for reconnecting the cord to the last said line and connecting the operator's telephone with the cord without the removal of either plug from its connected jack.

70

3. A telephone system comprising telephone lines, an operator's cord circuit, an operator's telephone, means responsive to the insertion of the answering and calling plugs into the jacks of telephone lines for automatically connecting and disconnecting the operator's telephone, cord disconnect means responsive to the replacing of the receiver of a connected line upon its switch-hook, and operator key controlled circuits for reconnecting the cord to said last line and connecting the operator's telephone to the cord without the removal of either plug from its connected jack.

75

4. A telephone system comprising telephone lines, an operator's cord circuit, an operator's telephone, means responsive to the insertion of the answering and calling plugs into the jacks of telephone lines for automatically connecting and disconnecting the operator's telephone, cord disconnect means responsive to the replacing of the receiver of a connected line upon its switch-hook, and operator key controlled circuits for reconnecting the cord to the last said line and connecting the operator's telephone to the cord without the removal of either plug from its connected jack.

80

5. A telephone system comprising telephone lines, an operator's cord circuit for connecting calling and called lines, an operator's telephone electromagnetically controlled means for connecting and disconnecting said operator's telephone and said cord circuit, means responsive to the replacing of the receiver of a connected line upon its switch-hook for conductively disuniting the opposite ends of the cord and operatively disassociating said cord from said line, and operator key controlled circuits for conductively uniting the opposite ends of the cord to said lines, and connecting the operator's telephone to the cord without the removal of either plug from its connected jack.

85

6. A telephone system comprising telephone lines, line signals for said lines, an operator's cord circuit, an operator's telephone, electromagnetically controlled means for connecting and disconnecting said operator's telephone and said cord circuit, means responsive to the replacing of the receiver of a connected line upon its switch-hook for operatively disassociating said cord and line, means responsive to a subsequent removal of the receiver of said line while the cord is still connected thereto for operating its line signal, and operator key controlled circuits for operatively associating the cord and the said line and connecting the operator's telephone to the cord.

- without the removal of either plug from its connected jack.
7. A telephone system comprising subscribers' lines, a link circuit for connecting said lines in conversational circuit, an answering supervisory signal, means associated with said link circuit responsive to subscriber control to operatively disassociate said link circuit from one of said subscribers' lines and to actuate said supervisory signal when said subscriber signals for disconnection, an operator's key, circuit connections controlled by said key for again associating said subscriber's line with the said link circuit when said subscriber signals for a recall and a relay energizable over the subscriber's line for effacing said supervisory signal.
8. A telephone system comprising subscribers' lines, a link circuit for connecting said lines, an operator's telephone, automatic means for connecting and disconnecting the said operator's telephone and said link circuit, subscriber controlled means for disassociating said link circuit from one of said subscribers' lines, an operator's key, and circuit connections controlled thereby for reconnecting the operator's telephone with the said link circuit and for reassociating the said link circuit with the subscriber's line.
9. A telephone system including subscribers' lines, a link circuit for connecting said lines, an answering supervisory signal, a relay associated with said link circuit adapted to be energized responsive to a control exercised over one of said subscribers' lines for operatively disassociating the said connected subscriber's line from the link circuit and for actuating said supervisory signal, an operator's key for said link circuit, and a circuit for said relay adapted to be opened by said key to restore said relay, whereby the said link circuit is again associated with said subscriber's line.
10. A telephone system comprising subscribers' lines, an operator's link circuit for interconnecting the said lines, an operator's telephone, automatic means for connecting and disconnecting said operator's telephone and said link circuit, means under the control of a connected subscriber for operatively disassociating his line from said link circuit, an operator's key for said link circuit, and circuit connections controlled by said key for reconnecting said link circuit with said subscriber's line and for reconnecting said operator's telephone with said link circuit.
11. A telephone system comprising subscribers' lines, an operator's link circuit for interconnecting the said lines, an operator's telephone, automatic means for connecting and disconnecting said operator's telephone and said link circuit, means under the control of a connected subscriber for operatively disassociating his line from said link circuit, an operator's key for said link circuit, and circuit connections controlled by said key for reassociating said link circuit with said subscriber's line and for connecting said operator's telephone with said link circuit.
12. A telephone system comprising subscribers' lines, a link circuit for connecting said lines in conversational circuit, a relay associated with said link circuit energizable responsive to subscriber control to operatively disassociate said link circuit from one of said subscribers' lines when disconnection is signaled for an operator's telephone, an operator's key, and circuit connections controlled by said key for again associating said line with the said link circuit by de-energizing said relay when said subscriber signals for a recall prior to the removal of either of the link plugs from their connected jacks and for connecting said operator's telephone with said link circuit.
13. A telephone system comprising subscribers' lines, a link circuit for connecting said lines, an operator's telephone, automatic means for connecting and disconnecting the said operator's telephone and said link circuit, subscriber controlled means for disassociating said link circuit from one of said subscribers' lines, an operator's key, and circuit connections controlled thereby for reconnecting the operator's telephone with the link circuit and for reassociating the link circuit with said subscriber's line, without the removal of either of the link circuit plugs from its connected jack.
14. A telephone system including subscribers' lines, a link circuit for connecting said lines, a relay associated with said link circuit and under substation control for operatively disassociating a connected subscriber's line from the link circuit, an operator's key for said link circuit, and a circuit for said relay controllable by said key and adapted to be opened when said key is operated to deenergize the same thereby again connecting said link circuit to said subscriber's line.
15. A telephone system comprising subscribers' telephone lines, a manual link circuit for connecting two of said lines in a conversational circuit, an operator's telephone, automatic means responsive to connection of said link circuit to a calling and a called one of said lines respectively for connecting and disconnecting the said operator's telephone and the said link circuit, electromagnetic means controlled at the substation of one of the connected lines for operatively disassociating said connected line from said link circuit and for restoring the subscriber's line circuit equipment to normal, an operator's key for said link circuit,

and circuit connections controlled by said key for reconnecting said operator's telephone with said link circuit and for reassociating said link circuit with said subscriber's line without necessitating the removal of the link circuit plugs from the line jacks of the connected lines.

16. A telephone system including subscribers' telephone lines, a cord circuit provided with terminals for connecting said lines in conversational circuit, an operator's telephone, means responsive to connection of the said terminals with a calling and a called one of said lines for automatically connecting and disconnecting said operator's telephone and said link circuit, means associated with said link circuit and controllable from the substation of the calling line for disassociating said link circuit from said calling subscriber's line when said calling subscriber signals for disconnection, and a key for said link circuit, said key being operable by a central office operator to cause said operator's telephone to be reconnected to said link circuit and to reassociate said link circuit with said calling subscriber's line.

17. A telephone system comprising subscribers' telephone lines, a link circuit provided with connection terminals for connecting said lines in conversational circuit, inductive devices normally connected to the strands of said link circuit and to said terminals, subscriber-controlled means associated with said link circuit for operatively disassociating said inductive devices from a connected one of the subscribers' lines, an operator's key and circuit connections controlled by said key for again associating said inductive devices with said subscriber's line prior to the disconnection of said connection terminals from said lines.

18. In a telephone system, the combination of a subscriber's line connected with a plug-ended link circuit, of an inductive device for said link circuit to which said plug is normally connected, subscriber-controlled means for disassociating said inductive device from said subscriber's line, an operator's telephone, an operator's key, and circuit connections controlled by said key for again associating said inductive device with said subscriber's line and for connecting said operator's telephone to said subscriber's line.

19. A telephone system comprising subscribers' lines, a link circuit provided with connection terminals for connecting said lines in conversational circuit, a battery supply relay normally connected with a strand of said link circuit for supplying talking current to one of said connected lines, means associated with said link circuit responsive to subscriber's control to operatively disconnect said battery supply relay from said

subscriber's telephone line, an operator's key, and circuit connections controlled thereby for again connecting said battery supply relay to said subscriber's line without disconnecting said connection terminals from said subscribers' lines.

20. In a telephone system, the combination of a link circuit connected to a subscriber's telephone line, of a battery supply relay normally connected to a conductor of said link circuit, means controlled solely over said subscriber's line for disconnecting said battery supply relay from said subscriber's line, an operator's key, and circuit connection controlled thereby for reconnecting said battery supply relay with said subscriber's line.

21. In a telephone system, a subscriber's telephone line connected with a plug-ended operator's link circuit, a battery supply relay normally connected with a contact of said plug, substation controlled means for disconnecting said battery supply relay from said plug, an operator's listening key, and means controlled by said key for reconnecting said battery supply relay with said plug.

22. A telephone system including a pair of subscribers' telephone lines, a link circuit provided with connection terminals for connecting said lines in conversational circuit, a relay for said link circuit for disconnecting one of the connected subscribers' lines from the said link circuit, a relay for said link circuit controllable over the said subscriber's line for energizing the said first relay, and a key for said link circuit for de-energizing the said first relay to again connect the subscriber's line with the link circuit prior to the disconnection of said connection terminals from said subscribers' lines.

23. A telephone system including a calling subscriber's telephone line, a link circuit provided with a connection terminal for connection therewith, a battery supply relay for said link circuit normally connected to said connection terminal, a relay for said link circuit controllable over said calling subscriber's line for disconnecting said battery supply relay from said subscriber's line, and a key for said link circuit controllable by a central office operator for deenergizing said disconnect relay to again connect said subscriber's line to said battery supply relay prior to the disconnection of said connection terminal from said subscriber's line.

24. A telephone system including a pair of subscribers' telephone lines, a link circuit provided with connection terminals for connecting said lines in conversational circuit, a relay for said link circuit for disconnecting one of the connected subscribers' lines from the said link circuit, a relay for said link circuit controllable over the said connected

subscriber's line for energizing the said first relay, and a key for said link circuit for deenergizing said first relay to again connect the subscriber's line with said link circuit.

25. A telephone system including a subscriber's telephone line connected with a plug-ended operator's link circuit, a battery supply relay normally connected to said plug, means for disconnecting said battery supply relay from said plug, substation controlled means for operating said first means, an operator's listening key, and means controlled by said operator's listening key for operating said first means to reconnect said battery supply relay to said plug.
26. A telephone system including a calling and a called subscriber's telephone line,

a link circuit provided with connection terminals for connecting said lines, a relay for said link circuit for disconnecting said calling subscriber's line from said link circuit, a relay for said link circuit controllable over said calling subscriber's line for actuating said first relay, and an operator's key for said link circuit for deenergizing said first relay to again connect said subscriber's line with said link circuit.

Signed by me at Cleveland, county of Cuyahoga, and State of Ohio, in the presence of two witnesses.
